UNITED STATES PATENT OFFICE.

CLAUDE LOUIS RAMEAU, OF PARIS, FRANCE.

MACHINE FOR GRINDING LENSES.

SPECIFICATION forming part of Letters Patent No. 772,431, dated October 18, 1904.

Application filed May 26, 1903, Serial No. 158,870. (No model.)

To all whom it may concern:

Be it known that I, CLAUDE LOUIS RAMEAU, civil engineer, a citizen of the Republic of France, and a resident of No. 110 Rue d'An-goulême, Paris, in the Republic of France, have invented certain new and useful Improvements in Machines for Grinding Lenses, of which the following is a specification.

This invention relates to improvements in machines for grinding lenses.

Machines for grinding lens-surfaces generally consist of two disks, either plain, convex, or concave, the lower disk being fixed or adapted to turn very slowly about its axis and the upper one movable, with its center usually describing a circle around the axis of the lower disk. In this movement the grinding material, such as pulp or dust, is constantly thrown toward the circumference and the grinding of the lens-surface is effected in an unequal and irregular manner. It would therefore be a great advantage to cause the center of one of the disks to describe round the fixed axis of the other disk a curve, so that the grinding material after being thrown toward the circumference would be brought back toward the axis.

The object of the present invention is a machine in which this result is secured by communicating to one of the disks an epicycloidal movement.

In the annexed drawings, Figure 1 shows the different forms of epicycloidal curves and the known way to construct them. Fig. 2 shows a complete elongated and closed epicycloid. Fig. 3 is a vertical sectional view of the device employed for producing the epicycloidal movement of one of the disks. Fig. 4 is a horizontal sectional view through line A B of Fig. 3. Figs. 5 and 6 are detail plan views of the device illustrated in Fig. 3. Fig. 7 is a whole elevation view of a model of construction of the new machine. Fig. 8 is a plan view of same.

It is known that the epicycloid is the curve generated by a point of a movable circle which rolls without sliding on a steady circle. If the circle B C rolls on the circle O A, Fig. 1, each point of the circle B C will describe an

epicycloid. If the point considered is on the circumference of the circle B C, the curve 1 or normal epicycloid will be obtained. If the point is inside the circumference, a shortened epicycloid will be obtained, of which the circle 2 described by the center B is a special case. 55 Finally, if the point is taken out of the generating circumference, as at D, for instance, the buckled curve 3 or elongated epicycloid will be formed. Fig. 2 shows this elongated epicycloid entire and closed after a suitable 60 number of revolutions. It is mainly this path that one will seek to impart to the grinding-disk during the working of the machine.

The machine comprises a standard *a*, supporting the different parts, a driving-shaft *b*, 65 a vertical shaft *c*, on the upper end of which is secured the lower disk *d*, and a second vertical shaft *e*, which carries the upper disk *f* by means of a joint hereinafter described. The lens-surfaces to be treated and the grinding 70 material are placed, as usual, between the disks *d* and *f*. The first vertical shaft *c* is given a slow rotary movement from the driving-shaft *b* through suitable gear—for instance, a pair of toothed wheels *g* and *h*, a worm *i*, mounted 75 on the shaft *j*, and a worm-wheel *k*, secured to the vertical shaft *c* and gearing with the worm *i*. The shaft *e* receives a rotary movement from the driving-shaft *b* through suitable pulleys *l m n* and a belt *p*. This shaft *e* carries a head *q*, resting on balls *r*, rolling in annular races in a part fixed to the frame. The said shaft is prolonged below the head *q* and carries a pinion *s*, gearing with another pinion *t*. These two pinions, of which the 85 number of teeth are prime one to each other, are mounted in a hoop or frame *u*, which is secured to the shaft *e* and rotates with it and rests, by means of a prolongation *v*, on balls *w*, rolling in annular races made in a piece integral with the frame. The teeth of the pinion *t* rolling round the pinion *s* an epicycloidal movement is thus given to said teeth, and the shaft *y* of said pinion *t* passes into or through the frame *u* and is carried along by it in its 90 rotation around the shaft *e*, but it can turn freely on itself in said frame. The shaft *y* extends downwardly and carries at its lower

end a horizontal plate z , having three parallel slots or recesses 5 , into which engage bolts or pins 6 , fixed to a tube or sleeve 7 . This sleeve carries the shaft 8 , which drives the upper 5 grinding - disk. An elastic connection— formed, for instance, by a helical spring 9 — may be interposed between the plate and the shaft which moves it. Owing to the grooves in the plate z and the said fastening-bolts the 10 shaft 8 of the sleeve can be made to coincide with the shaft y of the plate z or be moved therefrom. By these means it is possible for any point on the grinding-disk to describe a normal, elongated, or shortened epicycloid.

15 Having now described my invention, what I claim as new, and desire to secure by Letters Patent, is—

1. A machine for grinding lens-surfaces comprising a lower grinding-disk, a second 20 grinding-disk above the same, a vertical shaft, a frame rotatively carried thereby, a connection from said frame to the upper disk, means for rotating said connection and means for rotating the shaft, substantially as described.
- 25 2. A machine for grinding lens-surfaces comprising a lower grinding-disk, means for rotating said disk, a second disk above the first, a vertical shaft e , a frame rotatably carried thereby, a shaft y carried by said frame, 30 a shaft 8 carrying the upper grinding-disk and an adjustable connection between shaft y

and shaft 8 and means for rotating shaft e , substantially as described.

3. A machine for grinding lens-surfaces comprising a grinding-disk d secured on the 35 upper end of a vertical shaft c , means for causing said shaft c to turn, a second grinding-disk f arranged above the first one, a vertical shaft 8 pivoted centrally on the top of the disk f , a sleeve 7 in which is arranged the 40 shaft 8 , a plate z provided with parallel grooves 45 5 , bolts 6 engaged in said grooves and securing the sleeve 7 to the plate z in the proper position, a vertical round shaft y fixed on the upper surface of the plate z , a pinion t mounted on the shaft y , a vertical driving-shaft e arranged parallel to the shaft y and guided in the frame, a pinion s mounted on the shaft e and gearing with pinion t , a head q integral with the shaft e and resting on balls carried 50 by the frame of the machine, a hoop or frame u fixed to the shaft e and loosely passed over the shaft y , and means for causing the shaft e to turn, substantially as and for the purpose set forth.

In witness whereof I have hereunto set my hand in presence of two witnesses.

CLAUDE LOUIS RAMEAU.
